UNITED STATES PATENT OFFICE.

JOHN L. FAY, OF ST. LOUIS, MISSOURI.

GROUND-ANCHOR.

1,101,911.

Specification of Letters Patent. Patented June 30, 1914.

Application filed February 24, 1913. Serial No. 750,232.

To all whom it may concern:

Be it known that I, JOHN L. FAY, a citizen of the United States, residing at the city of St. Louis, State of Missouri, have invented a certain new and useful Improvement in Ground-Anchors, of which the following is a full, clear, and exact description, such as will enable others skilled in the art to which it appertains to make and use the same, reference being had to the accompanying drawings, forming part of this specification, in which—

Figure 1 is a vertical sectional view through my improved ground anchor. Fig. 2 is a top plan view of the same.

This invention relates to new and useful improvements in ground anchors, the object being to construct a device of the character described which may be of detachable units whereby the size of the anchor may be increased or diminished according to the holding power required.

In the drawings, 1 indicates the rod which extends to or above the surface of the ground, and to which is connected the guy rope or cable. This rod has a nut on its lower end by which it is connected to the upper unit or section 2 of my improved anchor. This section 2 is preferably in the form of the frustum of a cone and is provided with an outwardly extending flange 2^a at its base. The sides of the cone are provided with projections or lugs 2^b.

3 indicates a tapered ring having an inwardly extending flange 3^a at its upper edge, said flange having notches 3^b which are designed to register with the lugs 2^b of the section 2 and by slightly turning the section 3, locking the same against longitudinal displacement to the lower edge of section 2. Section 3 also has an outwardly extending flange 3^a at its lower edge and lugs 3^b for the purpose of coöoperating with the notched flange of the next section 4 of increased diameter as shewn in the drawing. There is also shown in the drawing another section 5. Additional sections of gradually increasing diameter can be employed until the desired base diameter of the anchor is secured. In practice, I have found that the majority of ground anchors used range from 7" to 13" in diameter and in practice the top unit or

section 2 would preferably be made 7" in diameter across the bottom whereby this single unit could be employed for ground anchors of this size. To increase the size of the anchor, a tapered ring would be secured to the top unit or as many rings as would be found necessary to secure the required diameter.

It will be observed when a single unit is employed or a plurality of units are used, that my improved anchor is tapered or is essentially conical in shape having shoulders or projections in the form of steps, which shoulders or projections add materially to the holding power of the anchor. In practice, after the hole is dug, it is usual to tamp stones in around the anchor, the upper portion of the hole being filled in with dirt. The stepped shoulders engaging the stones not only offer great resisting power against a pull on the rod, but the conical shape tends to force the stones laterally, and this wedging action also offers great resistance to dislodgment of the anchor.

By making the anchor in sections or units, it can be shipped collapsed and occupy a very small space, or when quantities are packed for shipment, the various sizes of rings may be nested one within the other so as to occupy little space in shipment.

What I claim is:

1. As a new article of manufacture, a ground anchor comprising a series of tapered ring sections which are graduated in size so as to form a hollow conical body when properly assembled, which ring sections can be readily assembled or taken apart to vary the diameter and height of the anchor, and means comprising coöoperating projections and notches on said ring sections, for holding the same in open position.

2. As a new article of manufacture, a ground anchor, the main body portion of which is composed of a series of collapsible members, each of which comprises a tapered ring section, an inwardly projecting flange on the upper edge of each section, there being a notch formed in said flange, an outwardly projecting flange on the lower end of each section, an integral projection on each section adjacent to the flange on the lower edge thereof, which projection is adapted to

pass through the notch in the flange at the top of the next adjacent sections to lock said tapered ring sections in open position, a hollow truncated conical member detachably connected to the upper one of the series of ring sections, and an anchoring rod attached to said hollow conical member.

In testimony whereof I hereunto affix my signature in the presence of two witnesses, this 4th day of February, 1913.

JOHN L. FAY.
